UNITED STATES PATENT OFFICE

HUGH J. JONES, OF DENVER, COLORADO

DISPLAY DEVICE

Application filed July 13, 1929. Serial No. 378,080.

My invention relates to display devices, and more especially to such devices which provide a series of separate displays which are changed successively in a continuous recurring cycle.

The object of my invention is to provide such a display device in which a curtain or shield is moved in front of the display and is held in place during the change from one display to another.

A further object is to provide such a display device in which double faced display cards may be employed and which during its complete cycle will display both faces of each card.

A further object is to provide such a display device in which each display card may be individually replaced or the display card unit may be easily removed and replaced by another display card unit, or by a unit having a number of set scenes similar to a toy theater, each scene of which is exposed in turn and the change from one scene to another being made during the time the curtain or shield is in front of the display.

I attain the above objects by providing a cabinet with a movable curtain or shield behind which is a revolvable display unit of either the card or the scene type, and by providing an operating mechanism unit which will move the curtain or shield, and revolve the display unit with the proper timing and sequence, as is more fully described below and is illustrated in the drawings, in which:—

Figure 1 is a front elevation in partial section of my display device.

Figure 2 is a fragmentary vertical longitudinal section through my display device.

Figure 3 is a plan view in partial section of my display device.

Figure 4 is a fragmentary elevation in partial section of the turntable, lower spider and turntable driving arm.

Figure 5 is a detail showing the mounting of the curtain or shield.

Figure 6 is a detail showing one curtain or shield and part of its actuating connections.

Figure 7 is a detail showing a side elevation of the card frame, and pivot yoke.

Figure 8 is a detail showing a top elevation of the card frame.

Figure 9 is a detail showing the tappet pin and mounting.

Figure 10 is a fragmentary detail on the line 10—10 of Figure 7, but with the pivot yoke separated from the card frame for the sake of clearness.

Figure 11 is a fragmentary detail showing a form of scene display unit.

The display shaft 1, journaled in the bearings 2 and 3, is provided with the turntable 4, which has the depending operating pins 5.

Whether display card unit or scene display unit is mounted in the device, the turntable, shaft and pins are substantially the same.

The mechanism for operating the turntable and the curtains or shields is also the same in either case, and will therefore be described first, and the details of the card display unit and of the scene display unit will be described later.

The electric motor 6, or any other proper prime mover, is properly connected to drive the pinion shaft 7 by means of the belt 8, or by any other proper form of driving connection.

The pinion 9 meshes with and drives the gear 10, which is securely mounted upon the worm shaft 11, whose worm 12 meshes with and drives the gear 13, securely mounted on the shaft 14.

Any other proper means of driving the shaft 14 from a prime mover may be employed so long as the necessary speed reduction is obtained whereby the shaft 14 will rotate at the necessary slow speed, as will appear below.

The shaft 14 is journaled at 15 and 16 in the frame 17, which also carries the journals 2 and 3 of the display shaft 1, journals the shafts 7 and 11, mounts the motor 6, and carries the entire actuating mechanism of the device as one self-contained unit, as will be further explained below.

The shaft 14 carries the cam 18, which in this form is shown as being integral with the gear 13, and also securely mounts the turntable driving arm 19. The turntable driv-

ing arm 19 is provided with the teeth 20 which co-operate with the turntable operating pins 5 upon each revolution of the shaft 14. This is, the teeth 20 are in effect a portion of a gear and they mesh with the pins 5 and rotate the table just as if the pins 5 were one gear and the arm 19 were another gear, but the duration of this driving engagement is such as to rotate the turntable at each revolution of the shaft 14 only the amount required to remove one display and to move the next succeeding display into place.

During the time between these short engagements of the arm 19 with the pins 5 the turntable remains stationary.

The lever 21, secured on the shaft 22 by the set screw 23, is provided with the ball 24 which rides upon the cam 18 at each revolution of the shaft 14.

20 The shaft 22 is journaled in the frame 17 and positioned endwise by the set collars 25.

The rocker shafts 26 are journaled in the frame 17, and are held therein by the set screws 27, which are received by a groove 25 in each shaft 26.

The rocker bellcranks 28 are mounted on the rocker shafts 26 and secured thereon by the set screws 29, the arms 30 being joined by the tension spring 31.

30 The pull of the spring 31 acts to maintain the bellcranks 28 in contact with the lever 21.

As the cam 18 contacts with and raises the ball 24 of the lever 21, the lever 21 rotates its shaft 22 and depresses the bellcranks 28, thus rotating the shafts 26.

35 The levers 32 are secured on the shafts 26 by the set screws 33, and are pivotally connected to the connecting rods 34, which in turn are pivotally connected to the levers 35, which are pivotally mounted at 36 upon the frame work of the cabinet 41.

The levers 35 are pivotally connected to the connecting rods 37, which in turn are pivotally connected to the curtain or shield 38.

45 The curtain or shield is divided into two parts which are slidably mounted on the rod 39 by the hangers 40.

50 In the operation of the display device, the prime mover, such as the motor 6, through its driving connection rotates the shaft 14 at the required speed. As the cam 18 contacts with the ball 24 and moves the lever 21, the bellcranks 28 are depressed, the shafts 26 are rotated, moving the levers 32, which 55 through the connecting rods 34, the levers 35 and the connecting rods 37 move the two parts of the curtain or shield till they come together at the center of the stage, in which position they are held by the cam 18 till it passes out 60 from under the ball 24.

During the time the curtains are closed the arm 19 contacts with and moves the pins 5, which rotates the turntable 1 to the next position, where it remains stationary. The 65 cam 18 and the teeth 20 of the arm 19 are

so proportioned and are so positioned on the shaft 14 with respect to each other, that as soon as the turntable reaches the new position the cam 18 begins to lower the ball 24, and the spring 31 acts to open the curtains and maintain the ball 24 in contact with the face of the cam 18.

The adjustable mountings of the levers 32 upon the shafts 26 permit the travel limits of the curtains to be adjusted as desired.

75 And the adjustable mountings of the bellcranks 28 permit both angular and longitudinal adjustments of the positions of the bellcranks and thereby assist in the travel adjustment of the curtains and to some extent 80 permit adjustment of the timing of their movements.

When it is desired to change from the card display to the scene display unit, the segment 42' is removed by taking out the screws 71', which hold the segment to the cross piece 60'.

85 This permits the curve of the floor of the scene display unit to take the place of the segment 42' of the floor 42.

90 When the shaft 1' of the scene display unit is mounted in the journals 15 and 16 of the frame 17, the unit is revolved by the arm 19 to present a new scene during each closure of the curtains 38.

95 The different scenes may contain any desired display or settings or advertising matter, and a new scene will be displayed after each closing of the curtains, for the entire cycle of scenes, which will then be repeated. It is understood that the teeth 20 of the arm 19 and the pins 5 of the turntable are to be constructed in each case to revolve whatever unit is in place, the exact amount required.

100 The construction of the card display unit is as follows:—The card frame is composed of the uprights 43, whose reduced ends are riveted through the frame base 46, and to which the top bars 44 and the bottom bars 45 are riveted, one top bar and one bottom bar on each side of the uprights. The card 51 is inserted between the top bars, passes down and rests between the bottom bars and is thus held in place by the top and bottom bars, the uprights, and the base.

105 The card 51 is provided with a display, picture, or other advertising matter upon each side.

110 The pivotal mounting pin 47 is provided with a hexagonal portion which rests against the bottom of the frame base 46, the pin being riveted through the base. The pin 47 of each card frame, passes through a hole in one of the spider arms 48, which arms are secured to the turntable and form the lower spider.

115 The spring 49 is mounted on the pin 47 and is held in resilient contact with the spider arm 48 by the washer 49' which in turn is held in place by the turning lever 50.

120 The friction thus maintained in the mount-

ing of the card frame on the spider arm holds the card frame in any position on the spider to which it may be moved.

A clevis 52 fits over the top bars 44 of each 5 card frame, and its locating pin 53 fits in the slots 44' of the top bars 44, while its pivot pin 54 fits through a hole in one of the spider arms 55, which arms are secured to the spider hub 56, and form the upper spider. The 10 spider hub 56 is secured upon the shaft 1 by the set screw 57.

When it is desired to change a card or to change all the cards in the card display unit, the set screw 57 is backed off, the upper spider 15 and the clevises are removed, and then any card or all the cards may be removed and replaced with other displays.

If it is desired to remove the entire card display unit, it is merely lifted bodily up- 20 ward, the shaft 1 pulling directly out of its bearings 2 and 3.

In the position shown in Figure 3, one card frame is in place as shown at 58 with the curtain open, the other card frames with their 25 cards being then in the positions shown.

After the curtains are closed by action of the cam 18, lever 21 and co-acting parts, as explained above, the card display unit is revolved, as indicated by the arrow, the card 30 frame 58 assuming the dotted line position 59, its angular position with its spider arm being changed by the contact of the rounded end of the frame base 46 with the cross piece 60 of the cabinet 41. Further movement 35 causes the following card frame 61 by its contact with 59 as indicated, to revolve the frame 59 slightly on its pivotal mounting on the spider arm till it will assume the position 62.

The tappet pin 63, secured to its mounting 40 64, is mounted on the frame of the cabinet 41 by the bolted nut 65, the slot in the mounting 64 permitting adjustment of the position of the pin 63, which adjusts the angular movement given the card frame on its spider arm.

45 When a card frame comes to the position indicated as at 66, its turning lever 50 contacts with the tappet pin 63 and further rotation of the unit turns the card frame 66 to the position shown as at 67.

50 The exact position to which the frame is thus turned is to be adjusted by proper positioning of the tappet pin 63, as mentioned above.

Further rotation of the unit then causes 55 the rounded end of the frame base 46 to strike the cross piece 60 of the cabinet 41 and thereby rotate the card frame on its pivotal mounting to the position shown as at 61, the final rotational movement of the unit bringing the 60 card frame to the final display position as shown at 58.

Thus, in each revolution of a card frame about the center of the shaft 1, it is positively turned on its spider arm so as to present its 65 other side to view.

That is, if the cabinet turntable and arm 19 are constructed for four card frames, each card will be displayed first on one side and then on the other side as the unit continues to revolve, making a total of eight displays 70 for the complete cycle.

If the construction is for three card frames there will be six displays to the cycle, and if the construction is for six card frames, there will be twelve displays for the complete cycle. 75

The cabinet may be lighted continuously by lights such as shown at 68, or the lights may be controlled by a switch such as shown at 71, which is automatically thrown in when the curtains begin to open and which is thrown 80 off during the time the curtains are closed.

It will now be seen that my invention provides a display device which gives the elements of suspense, and of surprise, both of which attract attention and interest of the on- 85 looker, with the result that he will almost certainly wait to see several changes of the display, perhaps an entire cycle, or even several cycles, so that what is being advertised will be impressed upon his mind. 90

I am well aware that various changes and alterations may be made to my device, which any competent mechanic will perceive which will not seriously change its value, and so I do not wish to confine my protection nar- 95 rowly to the exact constructions described and illustrated, but what I claim as new, and desire to protect by Letters Patent, is as follows:

1. In a display cabinet adapted to present a plurality of displays successively in a recurring cycle and to make the change from one display to the next during the time the curtains of said cabinet are closed, a frame, a revolving cam carried by the frame, a cam actuated lever, pivotally mounted on the frame, a pair of pivotally mounted shafts carried by the frame substantially parallel with said lever, a pair of arms adjustably secured upon said shafts and adapted to contact with and be actuated by said lever to give said shafts an oscillating movement, spring means adapted to maintain the lever in contact with the cam, and a pair of arms adjustably secured upon said shafts and connected to said curtains whereby at each revolution of the cam the curtains will be closed and will remain closed for a predetermined period of time, and will then be opened and remain open for a predetermined period of time. 100 110 120

2. In a display cabinet adapted to present a plurality of displays successively in a decurring cycle and to make the change from one display to the next during the time the curtains of said cabinet are closed, a frame, an oscillating lever mounted on the frame, a pair of oscillating shafts carried by the frame and each provided with an arm adjustably secured thereon and adapted to contact with and be actuated by said lever, spring 125 130

means adapted to maintain said arms in contact with said lever, and a pair of arms adjustably secured upon said shafts and connected to said curtains whereby at each oscillation of the lever the curtains are closed and again opened.

3. In a display cabinet adapted to present a plurality of displays successively in a recurring cycle and to make the change from one display to the next during the time the curtains of said cabinet are closed, a frame, a pair of oscillating shafts mounted on the frame, means carried by said shafts to adjust the angular extent of their oscillations, arms carried by the shafts and connected to the curtains whereby the curtains are closed and again opened at each complete oscillation of said shafts, and adjustable means securing said arms on said shafts whereby the position 20 of the curtains may be adjusted with respect to the shafts.

4. In a display cabinet having a display window and adapted to present in the display position at the display window a plurality 25 of display cards successively in a recurring cycle, a revolvable display card unit having upper and lower spiders provided with arms in pairs, and a display card frame having a base with rounded ends pivotally mounted upon each pair of arms, a turning pin carried by each of said frames, a tappet pin carried by said cabinet and adjustably mounted remote from said window and adapted to contact with the turning pin of each card frame 30 and thereby turn said frame on its pair of arms through a predetermined angle, and a member carried by said cabinet parallel with said window and adapted to contact with the leading rounded end of the base of each card frame and retard same and thereby further revolve each frame on its arms to bring the other face of said frame adjacent and parallel the said window.

5. In a display cabinet having a display window and adapted to present at the display window a plurality of cards successively in a recurring cycle, a revolvable display unit mounted in said cabinet and provided with a plurality of revolvably mounted card 45 frames with round ended bases and diametrically extending turning pins, an adjustably positioned tappet pin carried by the cabinet remote from said window and adapted to contact with the turning pin of each of said frames in succession and thereby turn each frame through a predetermined angle, and a member carried by said cabinet parallel with said window and adapted to contact with and retard the leading rounded end of each frame 50 base and thereby swing each frame on its mountings a further amount till the frame is parallel with said window.

6. In a display cabinet having a display window and adapted to display at the window a series of card displays in a recurring

cycle, a display unit mounted to have rotary movement in the cabinet, a plurality of card frames pivotally mounted on said unit and each provided with a turning pin and a frame base, a plurality of double faced cards in said frames, a tappet adjustably attached to the cabinet and adapted to contact with the turning pin of each frame in turn and to thereby revolve each frame with respect to its unit a predetermined amount, and a member parallel with said window and adapted to contact with the leading end of each frame base as the unit revolves and thereby revolve the frame with respect to the unit to bring the other end thereof to the leading position and the frame parallel with the window, whereby each frame will be revolved half a turn with respect to the display unit during each revolution of the unit and will thereby display first one face and then the other face of each card at the window.

7. In a display cabinet having a display window with curtains having a closed and an open position, and adapted to display at the window a series of card displays in a recurring cycle, a display unit mounted to have rotary movement in the cabinet, a plurality of card frames pivotally mounted on said unit and each provided with a turning pin and a frame base, a plurality of double faced cards in said frames, a tappet pin adjustably attached to the cabinet and adapted to contact with the turning pin of each frame in turn and to thereby revolve each frame with respect to its unit a predetermined amount, and a member parallel with said window and adapted to contact with the leading end of each frame base as the unit revolves and thereby revolve the frame with respect to the unit to bring the other end thereof to the leading position and the frame parallel with the window, whereby each frame will be revolved half a turn with respect to the display unit during each revolution of said display unit, and will thereby display first one face and then the other face of each card at the window.

8. In a display device, a display cabinet having horizontally reciprocating curtains, a display unit provided with a plurality of displays grouped about a central vertical shaft in the cabinet and adapted to rotate and present said displays successively in a display position back of said curtains, means to rotate said unit intermittently from one display position to the next, comprising drive members about said shaft and a continuously rotating toothed segment engaging said drive members at each revolution for a predetermined period, and means adapted to first open, and then close the curtains while said unit is stationary.

9. In a display cabinet having a display window and adapted to present at the display window a plurality of cards successively in

a recurring cycle and having horizontally reciprocating curtains co-operating with said window, a revolvable unit having a vertical shaft and provided with a plurality of displays, means adapted to open and again close the said curtains, means adapted to revolve said unit from one display to another intermittently, said revolution taking place while said curtains are closed, and including circularly spaced driving members and a continuously rotating toothed segment engaging said driving members at each revolution for a predetermined period, a prime mover, and a frame in the cabinet and mounting the prime mover, the curtain moving means and the unit revolving means and forming therewith an actuating unit.

10. In a display cabinet having a display window and adapted to present at the display window a plurality of displays successively in a recurring cycle and having movable curtains co-operating with said window and having a closed and an open position, a rotating display unit having a plurality of displays adapted to register successively with said window, and an actuating unit rotating about a vertical axis, and connections adapted to mount the display unit and means adapted to operate the curtains and to hold them in the closed position while the display unit is in motion and means to rotate said display unit comprising circularly spaced driving members and a continuously rotating toothed segment engaging said driving members at each revolution for a predetermined period.

11. In a display cabinet having a display window and adapted to present at the display window a plurality of displays successively in a recurring cycle and having movable curtains co-operating with said window and having a closed and open position, a rotating display unit rotating about a vertical shaft having a plurality of displays adapted to register successively with said window, an actuating unit adapted to rotatably mount said display unit, means connecting the display unit and the actuating unit in driving engagement whereby the display unit is revolved to register each display at the window successively and is held temporarily stationary after each display is moved to register with said window, comprising circularly spaced driving members and a continuously rotating toothed segment engaging said driving members at each revolution for a predetermined period of time, and means connecting the actuating unit with the curtains whereby they are operated and are held in the closed position while the display unit is in motion.

12. In a display cabinet having a display window and adapted to present at the display window a plurality of displays successively in a recurring cycle and having movable curtains co-operating with said window and having a closed and an open position, a plu-

rality of display units adapted to be received by and to operate in said cabinet selectively, and an actuating unit adapted to rotatably mount said display units selectively provided with means adapted to co-operate with the display unit in the cabinet to rotate the unit about a vertical axis intermittently to bring said displays successively to register with said window, and provided with means adapted to operate the curtains and to hold them in the closed position while the display unit is being moved, including circular drive members and a continuously rotated toothed segment engaging said members at each revolution for a predetermined period of time.

In testimony whereof I affix my signature.

HUGH J. JONES.
